(57) **CLAIM**

The ornamental design for a stanchion for vehicle loading, as shown and described.

DESCRIPTION

This application is related to and claims priority to U.S. patent application Ser. No. 12/653,610, entitled “Vehicle Loading Apparatus” (Donohue) filed on Oct. 16, 2009; and U.S. patent application Ser. No. 13/573,886, entitled “Vehicle Loading Apparatus” (Donohue) filed on Oct. 12, 2012.

FIG. 1 is a perspective view of a stanchion for vehicle loading showing my new design;

FIG. 2 is an illustrative perspective view thereof;

FIG. 3 is a rear view thereof;

FIG. 4 is a top view thereof;

FIG. 5 is a left view thereof;

FIG. 6 is a front view thereof;

FIG. 7 is a right view thereof; and,

FIG. 8 is a bottom view thereof.

The broken line showing in FIG. 2 is included for the purpose of illustrating environment and forms no part of the claimed design.
